UNITED STATES PATENT OFFICE.

THOMAS W. EATON, OF CHICAGO, ASSIGNOR OF ONE-HALF TO JOHN F. EATON, OF CAMBRIDGE, ILLINOIS.

OPERA-CHAIR.

SPECIFICATION forming part of Letters Patent No. 329,292, dated October 27, 1885.

Application filed December 27, 1883. Serial No. 115,746. (No model.)

To all whom it may concern:

Be it known that I, THOMAS W. EATON, of Chicago, in the county of Cook and State of Illinois, have invented certain new and useful 5 Improvements in Opera-Chairs; and I do hereby declare that the following is a full, clear, and exact description thereof, reference being had to the accompanying drawings, and to the letters of reference marked thereon, 10 which form a part of this specification.

The object of this invention is to provide an improved construction in opera or other folding chairs; and it consists in the matters hereinafter described, and pointed out in the 15 claims.

A principal feature of the invention consists in the combination, with a spring or weight for throwing the seat of a pivoted chair into a vertical position, of means for temporarily holding the seat in position for use, so constructed that the application of a weight to the seat sufficiently heavy to overcome the upward pressure of the seat-spring, as by a person sitting upon it, will cause the release 20 of such holding devices, and thereby permit the seat to rise upon the removal of the weight therefrom.

Several different forms of holding devices operating in the manner above stated are 30 herein shown as illustrating my invention, all of which embody the same general features of construction and comprise a movable detent upon the chair-seat, a projection upon the frame adapted for engagement with the detent, so as to hold the seat, when the latter is 35 in its horizontal position, from rising under the action of the spring or weight mentioned, the said detent and projection being so arranged that a further downward movement of the seat from the position in which the detent 40 and projection are engaged will carry the said detent out of engagement with the projection, and means constructed to prevent the re-engagement of the detent and projection after 45 they have become disengaged, so that the seat, when released, will be free to rise, as will hereinafter more fully appear.

A desirable form of device illustrating my invention is herein shown, in which a spring 50 is applied to arrest the downward movement of the chair-seat at the time it reaches a posi-

tion for the engagement of the detent with the projection upon the chair-frame, said spring being constructed to yield upon the application of considerable additional pressure to 55 the chair-seat, so as to permit the seat to sink slightly, and to thereby cause a further movement of the detent with reference to the projection, suitable means being provided, in connection with these devices, as above set 60 forth, for preventing the re-engagement of the detent with the projection when the pressure upon the seat is released.

In the accompanying drawings, Figure 1 is a central vertical section of an opera-chair, 65 illustrating one form of my invention, taken upon line $x-x$ of Fig. 2. Fig. 2 is a front or face view of the chair shown in Fig. 1. Figs. 3 and 4 are detail perspective views of devices for temporarily holding the chair in its horizontal position, which will be hereinafter more particularly described. Fig. 5 is a vertical detail section taken upon line $x-x$ of Fig. 1. Fig. 6 is a detail vertical section taken through the pivot of the chair-seat shown at 70 the right hand in Fig. 2. Fig. 7 is a detail end view of the pivot-pin shown in Fig. 6. Fig. 8 is a view illustrating another form of a device embodying my invention. Fig. 9 is a section taken upon line $x-x$ of Fig. 8. Fig. 10 80 is a detail view of another form of device, illustrating my invention. Fig. 11 is a fragmentary central vertical section of a chair, illustrating another form of my invention. Fig. 12 is a sectional view of the same, taken upon line 85 $x-x$ of Fig. 11. Fig. 13 is a vertical cross-section, illustrating the form of the device shown in Fig. 10, taken upon the line $x-x$ of said figure. Fig. 14 is a sectional view of a chair-seat, showing a weight applied to throw the 90 seat upwardly.

A are the side frames or standards of an opera-chair, generally of the usual construction. A' is the back thereof, and B is the seat, which is pivotally connected with the said 95 frame A, and is constructed to fold upwardly against the back A' when not in use.

In the form of device illustrated in Figs. 1, 2, 3, 4, 5, and 6 a spring, C, is applied to a stationary part connected with the side frame, 100 A, and having attachment with the seat B in such manner as to tend to throw the front edge

of the said seat upwardly and backwardly and to retain the seat in a vertical position. The said spring, as herein shown, and as illustrated in Figs. 2 and 6, is of spiral form, and is placed upon a cylinder, C', to which it is connected at one end by means of a lug, c', engaged with the hooked end c of the spring, and having its opposite projecting end, C², engaged with a stud, b, upon one of the side pieces, B', of the seat-frame, as illustrated in connection with the form of the device shown in Figs. 2 and 6, and also in connection with other devices embodying my invention in Figs. 8, 9, 11, and 12. The cylinder C' may be attached to the standard A outside of the seat, and concentric with the pivotal point thereof; but as herein shown said cylinder is located inside of the side piece, B', of the seat-frame, and is provided with a cylindrical extension, C³, which passes through a bearing, B², upon the side piece B', and is secured to the standard A, forming one of the pivots of the seat. The cylinder C' and pivot-pin C³ are, as shown, attached to the standard A by means of a bolt, C⁴, passing axially through said cylinder and secured in the said standard.

In order to enable the strength of the spring C to be adjusted to throw the seat upward with greater or less force, as desired, the end 30 of the cylindrical extension C³ of the cylinder C' is provided with radial corrugations c², fitted to corresponding corrugations in a recess, a, in the standard A, whereby the lug c' on the cylinder C' may be held at any angular 35 position found necessary in adjusting the spring.

The seat-frame, as illustrated in the figures above mentioned, is provided with a pivoted 40 detent, D, which is constructed to engage a stationary cam-plate, E, connected with the side frame, A, and which is shown as being located upon the inner face of the side piece, B', of the seat, and connected with the said side frame by means of a cylindrical projection, E', passing through a suitable bearing, B², upon the said side piece B', so as to form the pivot upon which the seat turns. The 45 detent D is preferably pivoted upon the inner surface of the side piece, B', of the seat, and its free end is bent at right angles, so as to form a projection, d, for engagement with a notch, e, upon the upper edge of the cam-plate E. The rear edge of the seat B is extended beyond the pivotal axis of the seat, 50 and rests upwardly against a spring, B³, (herein shown as being made of rubber,) which is inserted between the said seat and a stationary projection upon the chair-frame. Said spring is constructed to arrest the motion of 55 the seat, when thrown downwardly, at the point at which the detent D is in position to engage the notch e, but to yield upon additional pressure, so as to permit a further movement of the detent with reference to the notch. 60 The front wall of the notch e, as indicated at e' in Figs. 3 and 4, is curved upwardly and forwardly, so that when the front edge of the

chair is thrown downwardly from the point at which the said detent engages the notch said curved edge E' will cause the detent to rise 70 out of the notch. The detent D may be of sufficient weight to operate by gravity; or, if preferred, a spring, as shown at F, Fig. 1, may be applied to throw the said detent downwardly and to retain its end d in engagement with 75 the notch. Upon the inner face of the cam-plate E is pivoted a plate, G, which is provided with a notch, g, vertically above the pivotal point of the said plate G. The upper edge of the plate G extends slightly above the upper 80 edge of the cam-plate E, as indicated at g', and said plate G is provided with a weight, G', which tends, when the said plate is in a forward position, to throw the notch g forward with reference to the notch e, and when swung 85 backwardly past the pivotal point of the said plate G to throw the plate in the other direction, or rearwardly. The plate G is also provided at the rear end of the upper surface, g', with an upward projection or stop, g². 90

When the parts are in the position illustrated in Figs. 1 and 3, and the detent D is engaged with the notch e, so as to prevent the upward movement of the outer end of the chair-seat, and also with the notch g, the weight G' will be in position forward of the pivotal point of the plate G, and will tend to throw said plate forward and the surface g' beneath the end d of the said detent. If the outer end of the chair-seat is depressed by the 95 yielding of the spring B³, when the parts are in the position described, the action of the curved surface E' will cause the detent to be lifted from engagement with the notch e, and the parts will take the position illustrated in 100 Fig. 4, the weight G' causing the plate G to be rotated, so as to bring its upper surface, g', beneath the end of the projection d, and thereby prevent the return of the detent to engagement with the notch. Upon the release of 105 the seat, when in the position last described, (shown in Fig. 4,) the seat will be pressed upward by the spring C, and the detent, being held out of the notch e by the plate G, will be permitted to pass back over the upper edge 110 of the cam-plate G, so that the seat may rise to a vertical position. The purpose of the projection g² upon the plate G is to engage the 115 end of the detent, in order that the said plate may be thrown backwardly and the detent 120 caused to engage the notch e when the seat is again thrown downwardly. The pivot-pin E', which supports the side of the chair-seat, as 125 above stated, is provided with a square projection, e², upon its end, as shown more clearly in Figs. 3 and 4, which projection enters a corresponding recess, a', in the side A of the chair-frame. Said pivot-pin and the cam-plate E, attached thereto, are held rigidly in place by means of a bolt, E², herein shown as being secured in the side piece A. In practice, however, the side piece A would form the supporting-standard between two adjacent chairs, and the bolt E² would pass through said side 130

piece A and through the pivot-pin and cylinder C', for supporting the spring C of the adjacent chair-seat, so as to take the place of the bolt C⁴, above described, in supporting 5 said cylinder and pivot-pin.

The cam-plate E, instead of being located upon the inner face of the side piece B' of the seat-frame, may, obviously, be placed outside of said side piece, and be attached to 10 or form a part of the side piece A, the detent D in such case, of course, being attached to the side piece B', upon the outer surface thereof. The construction first described is, however, preferred, for the reason that the 15 cam-plate and devices connected therewith are thereby concealed from view, and are not liable to be interfered with by the occupant of the chair.

In Figs. 8 and 9 another form of the device 20 is shown embodying the same principles of operation. In this case, however, the part containing the notch for engaging the detent upon the chair-seat, and corresponding with the stationary cam-plate E, above described, 25 is movable, so that upon the withdrawal of the detent from the notch with which it is engaged, by the application of additional pressure to the outer edge of the chair-seat, the said part containing the notch will be moved so as 30 to prevent the return of the detent thereto, and thus permit the seat to return to its vertical position.

As shown in Figs. 8 and 9, the side piece A of the chair-frame is provided upon its inner face (adjacent to the pivotal point of the chair-seat at one side thereof) with a semicircular ring or projection, A², preferably, but not necessarily, concentric with said pivotal point. Upon the face of the said standard, 40 and below the seat-pivot, is placed a pivoted dog, H, with its free end extended rearwardly, and having in such free end a notch, h, formed by means of a rearwardly-projecting part, h', at the top of the dog. Upon the seat-frame, 45 at the rear of the pivotal point thereof, and preferably upon a downwardly-projecting arm, I', thereon, is pivoted a detent-arm, I, which projects forwardly, and is provided upon its free end with a transverse projection 50 or lug, i, which extends laterally to a point near the surface of the standard A, and into position to rest upon the annular projection A², so as to engage the notch h in the dog H. The said dog H is constructed to swing freely 55 upon its pivotal point, and normally rests at its free end upon the projection A², said projection having a notch at a², formed in its upper surface, constructed to receive the lower part of the free end of the dog, and to permit the projection h' upon the said free end of the dog to rest upon the said projection A². The dog H may be made of sufficient weight 60 to fall by gravity into the position described at a desired time; or, as shown, a spring, J, 65 may be provided for throwing said dog downwardly, said spring, if present, being prefer-

ably formed of a leaf attached at j to the rear portion of the semicircular projection A², and having its free end curved upwardly, so as to allow the detent projection to pass from beneath the same without noise, as will be hereinafter better understood. The chair-seat is in this construction thrown upwardly in a vertical position by means of a spring, C, placed upon a cylinder, C', both similar to the 70 corresponding parts first-mentioned. Said spring and cylinder may be placed at either side of the seat. As shown in the figures mentioned, however, the spring and supporting-cylinder therefor are placed at the 75 side of the seat adjacent to the devices described, for holding the seat temporarily in a horizontal position.

In Figs. 8 and 9 of the drawings the parts of the device last described are shown in the 80 position which they take when the seat is temporarily held horizontal, the lug i upon the detent I being engaged with the notch h upon the dog H, and the said projection or lug i resting upon the upper surface of the semicircular projection A², upon which surface it travels when the chair-seat is rotated. The parts being in the position described, it is obvious that when an additional weight or pressure is put upon the outer edge of the 85 chair-seat the spring B², between the rear edge of the seat and the chair-frame above it, will yield and will permit the lug i to recede beyond the rear of the projection h'. The dog H will then fall, and the point h' thereof will 90 rest upon the face of the annular projection A². The parts will remain in the position last stated until the pressure is removed from the seat. When such pressure is removed, as by the rising of the occupant, the seat, by the 95 action of the spring C, is raised, the lug i, in this movement of the seat, passing over the projection h' and dog H and beneath the spring J. After passing the dog H the lug i falls to the upper surface of the projection A², and 100 slides thereon until the chair has reached its vertical position. When it is again desired to place the seat in a horizontal position, a downward movement thereof will carry the detent-lug i backwardly upon the surface of 105 the projection A², and beneath the dog H, so as to lift said dog until it reaches the notch h therein, which it will engage, as before described. The spring B² is so located and is 110 of such strength that it will naturally arrest 115 the descending movement of the chair-seat at the moment the lug i engages the notch h, considerable additional pressure being required to further compress said spring sufficiently to carry said lug beyond the dog. The 120 spring J is preferably extended forwardly from its point of contact with the upper surface of the lug, and its end portion, j', is inclined upwardly from said surface, as before mentioned, so that when the lug i passes from 125 beneath the spring the upturned portion thereof will rest upon the lug and permit the 130

return of the spring to contact with the dog without the noise or click which might otherwise occur at such time.

In Figs. 10 and 13 still another equivalent form of device embodying the same general features of construction before described is illustrated. The chair-seat B may in this case be thrown upwardly by a spring or weight applied in any desired or preferred manner; but, as shown in said figure, a spring, C, constructed and operating in a manner previously described, is used for this purpose. Upon the rear edge of the chair-seat is placed a stationary lug or projection, K, formed, as shown, upon the bearing-block B² of the chair-seat, and constructed to engage a projection, l, upon a swinging arm or plate, L, which is pivotally connected with the side piece A of the chair-frame at the rear of the said projection. The plate L is arranged in a vertical position at some distance below the rear edge of the seat, when the latter is horizontal, and the upper end of said plate is constructed to swing freely, and is held normally in position to engage the lug K by means of a spring, L', which may be of any desired construction, but which, as herein shown, is similar to the spring C previously described, and is located at the pivotal point l' of the plate. The forward motion of the upper and free end of the plate L is preferably limited by means of a stop, l², upon the standard A. The projection l is located near the upper end of the plate L, and its lower surface is inclined in such a manner that when the free edge of the chair-seat is thrown downwardly the lug K, operating upon said inclined surface, will throw the plate L backwardly and permit the automatic engagement of the said lug with the said projection l, so as to hold the chair-seat in its horizontal position. Upon the upper end of the plate L is a pivoted dog, M, arranged in a generally horizontal position, and pivoted at its rear end, by means of a pivot-pin, m, to the plate L. The dog M is supported in a horizontal position by a stop, l², upon the plate L, and when it is in its normal position its forward or free end extends beyond the front edge of the plate L and the projection l thereon. By this construction, when the lug K is carried upwardly along the lower inclined surface of the projection l in lowering the seat, the upper edge of the said lug K will engage and lift the free end of the said dog, and support the latter in its raised position during the time that the said dog is engaged with the projection l, at which time the parts will be in the position illustrated in Fig. 10, and the seat will be held temporarily in its horizontal position. If, when the parts are in the position above mentioned, an additional movement of the seat takes place by the application of an increased pressure thereto, and the consequent yielding of the spring B³, the lug K will move upwardly and throw the free end of the dog M upwardly with it until the

forward and upward movement of the said lug K brings its end beyond the free end of the said dog, when the latter will drop and its end face will engage the said lug K. If, now, the front edge of the seat is released by the removal of pressure therefrom, the lug K will swing downwardly and carry the free end of the dog M downwardly with it until the motion of said dog is arrested by the stop l³. This movement of the lug and the dog M will obviously throw the upper end of the plate L backwardly into the position indicated by dotted lines in Fig. 10, and will thereby cause the release of the lug K from the projection l, so that said lug will be free to pass downwardly over said projection, and thus permit the seat to rise under the action of the spring. The dog M is preferably, as shown, provided with a projection, m', at its upper and free end, so that when the said free end of the dog drops into engagement with the lug K, in the manner above described, its downward motion will be arrested by the contact of the said projection m' with the lug K, and it will remain properly in engagement with said lug until the dog has reached its horizontal position and the lug is disengaged therefrom.

Another equivalent construction to those already described is illustrated in Figs. 11 and 12, in which the release of the detent upon the seat from the projection or dog upon the chair-frame is accomplished by a movement of the cushion or part of the cushion instead of by a further movement of the entire seat-frame, as in the form of the device herein-before described, and shown in Figs. 8 and 9. In this case the seat-frame is constructed to rest at its rear edge against a stationary cross piece or stop, A³, upon the chair-frame, no provision being made for supplemental movement thereof, and the part I', carrying the detent I, is necessarily an arm, and is pivoted to a horizontal shaft, P, upon the chair-seat. The shaft P rotates in bearings p upon the rear lower edge of the chair-seat, said bearings being, as herein illustrated, made upon the casting B², forming the bearing-box of the seat. At the middle of the shaft P, as shown more clearly in Fig. 12, is rigidly secured a forwardly-extending arm, P', which is engaged at its forward and free end with a lug, p', secured at or near the middle of a board, B⁴, which forms the foundation of the cushion of the seat, and which is made separate from and vertically movable with relation to the seat-frame. The board B⁴ and the free end of the arm P' may be held at the upper limit of their movement by any suitable spring applied between such parts and the said frame in any desired manner. As herein shown, however, a semi-elliptical spring, R, is employed, and secured by means of staples r at either end to the side pieces, B', of the seat-frame, and attached at its middle to the board B⁴. A stop or ledge, b', is preferably secured to the inner surface of the seat-frame, in order to limit the down-

ward movement of the movable board, and the spring R is so arranged as to hold said board slightly above the said ledge b', in order that upon the weight of a person coming upon 5 the seat the cushion may be depressed until it rests upon the said ledge. The arm P' being connected with the board B' of the cushion in a manner described, this depression of said cushion will cause the shaft P to be rotated 10 and the arm I' to be thrown backwardly, thus carrying the detent I to the rear and releasing its free end from engagement with the notch h, in the same manner that the detent is released from the dog H by the backward movement 15 occasioned by the rotation of the entire seat-frame, as described in connection with the device shown in Figs. 8 and 9. The spring for temporarily retaining the detent upon the seat in engagement with the projection or notch 20 upon the chair-frame, or part connected therewith, may in the device last described, and also in those before mentioned, be inserted between the movable part and a stationary part of the seat or chair frame at any desired 25 place.

In Fig. 14 of the drawings a weight, Q, is shown as attached to the rear edge of the seat B, said weight serving, instead of the spring C, (shown in the figures previously described,) 30 to throw the seat upwardly when the latter is released.

In another application, Serial No. 146,741, for patent, filed by me October 29, 1884, is shown and described another way of carrying 35 out the invention herein broadly claimed. The mechanism shown and specifically claimed in said application embodies, however, the same general features of construction and operation as are present in the devices herein shown and 40 above set forth, and said mechanism is therefore covered by the broad claims hereto appended.

I claim as my invention—

1. The combination, with the chair-frame 45 and pivoted seat, of a spring or weight applied to throw the seat upwardly, and mechanism for holding the seat in a horizontal position against the action of the said spring, comprising a projection and a detent upon the 50 seat and frame located in position for mutual engagement when the seat is horizontal, said projection and detent being relatively movable to permit their engagement with each other in the downward movement of the seat, a 55 spring or its equivalent applied to hold the said projection and detent normally in position for engagement, and means constructed to

move and hold the detent out of engagement with the projection when the said detent and projection are relatively moved by a downward movement of the seat from its horizontal position, whereby the seat will be free to rise when the pressure thereon is removed, substantially as described. 60

2. The combination, with the chair-frame 65 and pivoted seat, of a spring or weight applied to throw the seat upwardly, mechanism for holding the seat in a horizontal position against the action of the said spring, comprising a detent and a projection upon the seat 70 and frame located in position for mutual engagement when the seat is approximately horizontal, said projection and detent being relatively movable to permit their engagement and disengagement with each other, a 75 spring or its equivalent applied to hold the said detent and projection normally in position for engagement, and means constructed to move and hold the detent out of engagement with the projection when the said detent 80 and projection are relatively moved by a downward movement of the chair-seat from its horizontal position, and a spring interposed between the seat and a part of the frame, constructed to arrest the downward movement of 85 the seat in position for engagement of the detent and projection, and to yield when additional downward pressure is applied to the seat, substantially as and for the purpose set forth. 90

3. The combination, with the chair-frame 95 and pivoted seat and a spring or weight applied to throw the seat upwardly, of a notched plate upon the frame and a spring-actuated detent upon the seat, the said detent being located in position to engage the notch of the plate when the seat is approximately horizontal, and a movable part, as G, upon the said plate, located in position to engage the detent when the said detent has been carried out of 100 the notch by a downward movement of its seat from its approximately-horizontal position, and a spring or weight applied to throw said movable part G into position to engage said detent, substantially as and for the purpose set 105 forth.

In testimony that I claim the foregoing as my invention I affix my signature in presence of two witnesses.

THOMAS W. EATON.
